UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FEEDING MECHANISM FOR SEWING-MACHINES.

1,217,328.

Specification of Letters Patent. Patented Feb. 27, 1917.

Application filed February 26, 1912. Serial No. 679,980.

To all whom it may concern:

Be it known that I, JAMES R. MOFFATT, a citizen of the United States, residing at Chicago, in the county of Cook, State of Illinois, have invented certain new and useful Improvements in Feeding Mechanism for Sewing-Machines, of which the following is a description, reference being had to the accompanying drawing and to the figures 10 of reference marked thereon.

The invention relates to new and useful improvements in sewing machines, and more especially to the feeding mechanism therefor.

15 An object of the invention is to provide a differential feeding mechanism which is especially adapted for operation in connection with a multiple needle stitching mechanism, wherein the needles are widely spaced.

In the drawings which show by way of illustration one embodiment of the invention,

25 Figure 1 is a front view of a sewing machine having my improvements applied thereto;

Fig. 2 is a plan view of the mechanism beneath the work support;

Fig. 3 is a partial end view and a partial 30 vertical sectional view, showing the feeding mechanism in side elevation;

Fig. 4 is a vertical sectional view centrally through the feeding mechanism;

Fig. 5 is a detail showing the manner of 35 oscillating the feed rocker;

Fig. 6 is a detail perspective view with the parts separated showing several of the main features of the feed-supporting mechanism;

40 Fig. 7 is a detail in perspective, showing the bracket coöoperating with the eccentric which raises and lowers the main feed;

Fig. 8 is a detail in perspective, showing the yoke for supporting the auxiliary feed 45 dog;

Fig. 9 is a detail in perspective of the plate which engages the under face of the eccentric for raising and lowering the feed dog; and

50 Fig. 10 is a sectional view showing a com-

bined facing and binding strip attached to a fabric and the relative position of the auxiliary feed dog.

In carrying out the invention, I have provided a sewing machine consisting of a bed 55 plate 1, an overhanging arm 2 and a work support 3. A needle lever 4 is pivoted to the overhanging arm, and is oscillated from the main shaft by an eccentric strap 5. A needle bar 6 is reciprocated in the needle 60 head at the forward end of the overhanging arm by the lever 4. Said needle bar carries a cross head 7, at one end of which are mounted two needles 8; and at the other end of which is a single needle 9. The machine 65 is also provided with thread guides and tensions for the needle threads. These parts are of the usual construction, and will not need further description in this connection.

Coöoperating with each needle beneath the 70 work support is a looper 10. These loopers are mounted on a shaft 11 and are adjustably attached thereto so that the loopers may be shifted when it is desired to vary the distance between the lines of stitching. The 75 looper shaft 11 is mounted to oscillate in bearings formed in the brackets 12, 12.

At the outer end of the looper shaft is an arm 13, which is connected to a link 14 and the link in turn is connected to a crank pin 80 15 on a crank disk carried by the outer end of the main shaft. These loopers are of the ordinary non-thread-carrying type, and are moved into and out of the needle loops as the main shaft rotates, through the oscillations of the looper-supporting shaft by the mechanism above described.

While I have shown non-thread-carrying loopers coöoperating with the needles, it is apparent from certain aspects of the invention, that the particular stitch-forming mechanism is immaterial and other types of stitch-forming mechanism may be used.

In order to feed the material to the stitching mechanism, I have provided a feeding 90 mechanism which consists of a series of main feed dogs 16 and a series of auxiliary feed dogs 17. The main feeding device is formed with fabric-engaging dogs located adjacent the needles, and a pair of fabric-engaging 100

dogs located intermediate the needles. The main feed dogs are carried by a cross bar 18. Said dogs are adjustably secured thereto so that they may be independently adjusted in a direction transverse to the line of feed. This cross bar 18 is formed with a depending support 19, which fits in a recess 20 carried by a plate 21, which is a part of the main feed bar.

10 The support 19 is slotted vertically, and a screw 22 passing through the slot holds the support in various adjusted positions. The plate 21 is mounted on the main part of the feed bar 23, by suitable bolts. This main feed bar 23 is formed with spaced arms, and each of the arms is secured to a pivot pin, which is journaled in the feed rocker 24. This feed rocker 24 is pivoted at 25 to ears formed on the bed plate 1 of the machine.

15 The feed rocker is moved back and forth from an eccentric on the main shaft, through an eccentric strap 26, (see Fig. 5) which is pivoted to an arm 27 rigidly connected to the feed rocker 24.

20 As the main shaft rotates, the feed rocker will be oscillated, and will cause the feed bar to move back and forth in substantially a horizontal plane. The lower face of the feed bar 23 rests on an eccentric 28.

25 An arm 29 is rigidly secured to the feed bar and projects underneath the eccentric. This arm and the feed bar form a yoke, and as the eccentric 28 rotates, the feed bar will be positively raised and lowered to cause the main feed dog to engage the fabric.

30 From the above description, it will be apparent that as the main shaft rotates, the feed rocker will be oscillated, and the main feed dogs moved back and forth, and the main feed bar will also be raised and lowered in proper timed relations to the oscillations of the feed dogs, to cause said feed dogs to engage and feed the fabrics, and to 45 be disengaged therefrom for their return stroke.

35 As a means for supporting and operating the auxiliary feed dogs, I have provided the supporting plate 21 for the main feed dog with laterally projecting spaced lugs 30, each of which is perforated and serves as a bearing for side rods or bars 31. These side bars or rods are adapted to slide in the perforated lugs 30.

40 At their rear ends, each bar carries a collar which is attached to a cross rod 32. A link 33 is provided with a sleeve which is journaled on the rod 32, and the rear end of the link is provided with a pivot bolt 34 adapted to be adjustably fixed in a segmental slot 35, formed in a bracket arm 36 carried by the main feed rocker 24.

45 By loosening the pivot bolt 34, the same may be raised or lowered in the slot, and the

distance of the pivotal connection between 65 the bracket arm and link 33 from the fulcrum of the feed rocker varied. If the pivot bolt 34 is thrown to the lower end of the slot in the bracket arm, then said pivot bolt is substantially in line with the pivotal 70 points between the main feed bar and the feed rocker, and there will be no reciprocating movement of the side rods or bars 31 relative to the supporting plate therefor. If, however, the pivot bolt is raised from 75 the lower end of the slot, a slight reciprocating movement of the bars relative to the supporting plate 21 will result, and the amount of reciprocating movement between these parts will depend upon the adjustment of the pivot bolt in said segmental slot.

50 At the forward end of the bars 31 is adjustably mounted a yoke 37. This yoke consists of side arms 38 which carry collars 35 adapted to engage the ends of the rods or bars 31, and be firmly but adjustably secured thereto. Said yoke also consists of a cross bar 39, which is bolted to the ends of the side arms 38. This cross bar 39 is 90 formed with a slot 40.

55 The auxiliary feed dogs 17 are all mounted on a common shank which is formed with a depending support 41. Said support is formed with a vertical slot. A bolt 95 42 passing through the vertical slot is provided with a nut which laps the sides of the slot 40 and is capable of sliding longitudinally therein. By loosening this screw 42, the auxiliary feed dogs may be raised and 100 lowered relative to the cross bar, or they may be moved longitudinally of the cross bar.

60 In order to form a rest for the feed bar, I have provided screws 43, which are mounted in the upper edge of the cross bar 39. 105 The shank of the auxiliary feed bar rests on these screws. The screws may be raised and lowered, and thereby form an adjustable seat for the auxiliary feed bar.

65 As above noted, the supporting bars or 110 rods for the auxiliary feed dogs are given a differential movement relative to the supporting plate for the main feed dogs, and, therefore, the auxiliary feed dogs will be given a differential feed movement.

70 If the link 33 is adjusted so that the pivot bolt is carried to the lower end of the segmental slot 35, then the auxiliary feed dogs will move in unison with the main feed dogs.

75 By this construction, wherein the auxiliary feed dogs are carried by a yoke attached to side bars, I am able to provide sufficient space for the operation of the loopers and needles, although said needles may be widely spaced. Furthermore, by 125 this construction I have provided a feed dog-supporting means, which will not be liable to tilt or cramp in any way due to

any uneven pressure thereon. The feed dogs may be adjusted laterally, in order to accommodate the different spacing of the needles. Said feed dogs may also be adjusted vertically so as to be brought into proper coöperative engagement with the fabric.

The differential feeding mechanism above described is especially adapted for coöperation with the widely spaced needles of a multiple needle stitching mechanism. In Fig. 1 I have shown a folder 44, which is adapted to fold a strip of fabric so that one face thereof is much wider than the other, and invert the same as it passes to the stitching mechanism. This strip of fabric when attached to the body fabric becomes a combined facing and binding strip.

One of the special purposes of a machine of this character is for placing a binding and facing strip on to an elastic or knit fabric. A great deal of trouble is experienced in stitching a non-elastic binding strip to an elastic body fabric, owing to the fact that the drag or friction of the operating parts on the elastic goods unduly stretches the same. By the present mechanism, however, where the auxiliary feed dogs are located in front of the stitching mechanism, and also so disposed as to engage the knit fabric only, as clearly shown in Fig. 10, said knit fabric may be fed a little faster to the stitching mechanism, in order to make up for any undue stretching, and thereby the elastic fabric fed as evenly and smoothly as the non-elastic fabric.

It is obvious that minor changes in the details of construction may be made, without departing from the spirit of the invention, as set forth in the appended claims.

Having thus described my invention, what I claim as new and desire to secure by Letters Patent, is:—

1. The combination of stitch forming mechanism and feeding mechanism, said mechanism including a main feed bar, feed supporting bars carried thereby and projecting forwardly therefrom, one on each side of the needle of the stitch forming mechanism, a cross support carried by said supporting bars and located wholly in front of the needle, a feed dog detachably connected to said cross support and means for moving the feed supporting bars independently of said main feed bar.

2. The combination of stitching mechanism including a needle and feeding mechanism including feed-supporting bars one on each side of the needle and extending in front thereof, a cross support carried by said bars, a feed dog, means for attaching said feed dog to said cross support, whereby said feed dog may be adjusted vertically and also longitudinally of said cross bar.

3. The combination of stitching mechanism including a needle and a feeding mechanism including a main feed bar, a bracket secured to said feed bar and projecting laterally therefrom at opposite sides of the feed bar, auxiliary feed supporting bars mounted in said projecting portions of the bracket and located on opposite sides of the needle and extending in front thereof, an auxiliary feed dog adjustably carried by said feed supporting bars and projecting rearwardly toward the needle, said auxiliary feed dog being located wholly in front of the needle.

4. The combination of stitching mechanism including a needle and a feeding mechanism including a main feed bar, feed dogs carried thereby, auxiliary feed-supporting bars carried by the main feed bar, located one on each side of the needle and extending in front thereof, an auxiliary feed dog carried by said auxiliary feed bar, and means for imparting a differential movement to said auxiliary feed-supporting bars.

5. The combination of a main feed bar, a feed dog supported thereby, auxiliary feed bars located one on each side of the main feed dog and extending in front thereof, and an auxiliary feed dog carried by said auxiliary feed bars.

6. The combination of a main feed bar, a feed dog supported thereby, auxiliary feed bars located one on each side of the main feed dog and extending in front thereof, an auxiliary feed dog carried by said auxiliary feed bars, and means for imparting a differential movement to said auxiliary feed dog.

7. The combination of a main feed bar, a main feed dog carried thereby, auxiliary feed bars slidingly supported by the main feed bar and located one on each side thereof, said auxiliary feed bars extending in front of the main feed dog, and an auxiliary feed dog carried by the said auxiliary feed bars.

8. The combination of a main feed bar, a main feed dog carried thereby, auxiliary feed bars slidingly supported by the main feed bar and located one on each side thereof, said auxiliary feed bars extending in front of the main feed dog, an auxiliary feed dog carried by the said auxiliary feed bars, and means for imparting a differential movement to said auxiliary feed dogs.

9. The combination of a main feed bar, a feed rocker to which said main feed bar is pivoted, a main feed dog carried by said main feed bar, auxiliary feed bars one located at each side of said main feed bar and projecting in front of the main feed dog, an auxiliary feed dog carried by said auxiliary feed bars and located in front of said main feed dog, means for raising and lowering the main feed bar, and means connect-

- ing said feed rocker with the auxiliary feed bars for imparting a differential movement to the auxiliary feed dog. 15
10. The combination of a main feed bar, a feed rocker to which said main feed bar is pivoted, a main feed dog carried by said main feed bar, auxiliary feed bars one located at each side of said main feed bar and projecting in front of the main feed dog, an auxiliary feed dog carried by said auxiliary feed bars and located in front of said main feed dog, means for raising and lowering the main feed bar, a bracket carried by said main feed rocker and having a segmental slot therein, a pivot bolt adjustable in said slot, a link connecting said pivot bolt to the auxiliary feed bars. 20
11. The combination of a main feed bar having spaced rearwardly projecting arms, a feed rocker having spaced arms pivotally connected to the spaced arms of the main feed bar, a slotted bracket carried by the feed rocker and located between the spaced arms thereof, a main feed dog carried by the main feed bar, an auxiliary feed bar slidably supported by the main feed bar, a link connected to the auxiliary feed bar and to said slotted bracket for giving the auxiliary feed bar a differential movement, and an auxiliary feed dog carried by the auxiliary feed bar. 25
12. The combination of a main feed bar, a plate carried thereby, a main feed dog supported by said plate, said plate having bearings extending from each side thereof, bars slidably mounted in said bearings, a yoke connected to the forward end of said bars and located in front of the main feed dog, an auxiliary feed dog carried by the yoke, and means for reciprocating said bars in said side bearings for imparting a differential movement to the auxiliary feed dog. 30
13. The combination of a main feed bar, a plate carried thereby, a main feed dog supported by said plate, said plate having bearings extending from each side thereof, bars slidably mounted in said bearings, a yoke connected to the forward end of said bars and located in front of the main feed dog, an auxiliary feed dog carried by the yoke, means for reciprocating said bars in said side bearings for imparting a differential movement to the auxiliary feed dog, and means for raising and lowering the main feed dog. 35
14. The combination of a main feed bar, a feed rocker to which said main feed bar is pivotally connected, means for raising and lowering the main feed bar, a plate carried by said main feed bar, a plurality of feed dogs adjustably mounted on said plate, said plate having laterally projecting bearings, bars mounted to slide in said bearings, a yoke connected to the forward end of said bars, auxiliary feed dogs adjustably carried by said yoke, a cross bar connecting the rear ends of said side bars, a link pivotally connected to said cross bar, a slotted bracket carried by the feed rocker, and a pivot bolt carried by said bracket to which the other end of said link is pivoted. 40
15. A sewing machine including in combination, stitch-forming mechanism including a looper, a main feeding mechanism including a main feed bar, a feed dog carried thereby, supplemental feed bars located side by side, said bars being spaced and carried by said main feed bar and projecting in advance of the looper, said supplemental feed bars being movably carried by said main feed bar, an auxiliary feed dog carried by said auxiliary feed bar, said feed dogs and said auxiliary feed bars outlining a space containing the looper. 45
16. A sewing machine including in combination, stitch-forming mechanism including a looper, a support for said looper, and a feeding mechanism including a main feed bar located in rear of said looper support, a main feed dog carried thereby, auxiliary feed bars located side by side on opposite sides of the looper and extending to a point in advance of said looper support, an auxiliary feed dog supported thereby, means for moving said main feed bar, and means for giving said auxiliary feed dog a differential movement relative to said main feed dog. 50
17. A feeding mechanism for sewing machines including in combination, a main feed bar, a main feed dog carried thereby, a plurality of auxiliary feed bars located side by side, said feed bars being spaced from each other and carried by said main feed bar, means connecting said auxiliary feed bars at a point in advance of the main feed dog, and an auxiliary feed dog carried by said auxiliary feed bars. 55
18. A feeding mechanism for sewing machines including in combination, a main feed bar, a main feed dog carried thereby, a plurality of auxiliary feed bars carried by said main feed bar, means connecting said auxiliary feed bars at a point in advance of the main feed dog, and an auxiliary feed dog carried by said auxiliary feed bars. 60
19. In a sewing machine, a feeding mechanism comprising a main feed bar, a main feed dog carried thereby, said main feed bar carrying a plurality of supplemental feed bars located side by side and spaced from each other, said supplemental feed bars being movable relative to the main feed bar and connected in advance of the main feed bar and carrying adjustable feed dogs in

the space between the supplemental feed bars.

20. In a sewing machine, a feeding mechanism comprising a main feed bar and a differential feed bar, said main feed bar carrying a plurality of supplemental feed bars, feed dogs supported by said supplemental feed bars in advance of the main feed bar, said supplemental feed bars at their rear

ends being connected with means to give a forward and backward movement to said supplemental bars.

In testimony whereof, I affix my signature, in the presence of two witnesses.

JAMES R. MOFFATT.
